UNITED STATES PATENT OFFICE.

RAYMOND C. BENNER, OF BAYSIDE, NEW YORK, ASSIGNOR TO NATIONAL CARBON COMPANY, INC., A CORPORATION OF NEW YORK.

APPARATUS FOR RADIO COMMUNICATION.

Application filed February 28, 1922. Serial No. 539,883.

To all whom it may concern:

Be it known that I, RAYMOND C. BENNER, a citizen of the United States, residing at Bayside, in the county of Queens and State 5 of New York, have invented certain new and useful Improvements in Apparatus for Radio Communication, of which the following is a specification.

In radio communication, an electron tube 10 is commonly used in conjunction with one or more series-connected batteries, each comprising several cells, and usually termed a "plate battery" or "B" battery. This combination is used, in known manner, in connection with a wide variety of apparatus, a 15 telephone being ordinarily arranged in some portion of the installation to transform the energy of electrical currents flowing through the circuit into audible emissions.

20 The battery of such a combination may comprise, for example, fifteen series-connected dry cells. In assembling dry cells into a series-connected battery, it has been usual to arrange the cells in a plurality of 25 closely spaced rows in order to secure a compact package. I have discovered that when the battery is to be used in a combination of the kind described, a decided improvement in action is obtained if the 30 units are arranged in a single line.

For illustration, my invention will be described in connection with an embodiment which includes a battery, an electron tube and a telephone, reference being had 35 to the accompanying drawing, wherein is shown diagrammatically, the combination of electron tube, "B" battery, and telephone as modified and improved in accordance with my invention.

40 Without limiting myself to any particular theory of operation, I may state that my present knowledge leads me to ascribe the improvement to the following:

In the arrangement of cells now generally 45 employed, there are shown fifteen cylindrical dry cells disposed in three rows of five cells each. The line of current flow in any two adjacent rows may be likened to a letter U, the vertical strokes of the letter representing 50 rows of cells and the connection between these vertical strokes representing the electrical connection between the end cells in the two rows. With such an arrangement, the rows being disposed close together to 55 save space, the potential differences between

certain adjacent cells are multiples of the E. M. F. of a single cell. This potential difference between adjacent cells reaches a maximum between the cells located at adjacent ends of the rows at the points corresponding to the top extremities of the U. It is, of course, the zinc electrodes which approach one another most closely and at this point the potential difference between adjacent zincs is the product of the E. M. F. of a single cell by a factor which is the total number of cells in the two rows, diminished by 1, or 9 in the particular case referred to. This potential difference may exceed 13 volts in the example.

The insulation requirements in such a circuit are very rigorous since the telephone is adapted to be operated by very minute currents, and exceedingly minute current variations superposed on the operating current suffice to interfere seriously with the action of the telephone. Under the conditions noted, with comparatively high potential differences between closely adjacent parts of the circuit, adequate insulation becomes a 70 difficult matter. The access of moisture to the insulation and especially the access of electrolyte which may be exuded from the cells, may suffice to permit the leakage of 75 currents of such magnitude as to alter the terminal voltage of the battery, the fluctuations being small but nevertheless sufficient to affect the telephone seriously. Leakage currents set up in this way are 80 not constant but fluctuate continually because of polarization of the surfaces between which they flow and because of other variables, and these fluctuations are all converted into audible vibrations at the telephone and superposed upon the normal 85 function of the instrument, thereby interfering with its operation.

I also regard it as possible that the condenser action of such a battery is an additional disturbing factor, being not only a 90 distributed capacitance but one subject to fluctuations, for reasons similar to those which may occasion fluctuations in current leakage.

I have found by actual test that a receiving apparatus using a "B" battery with flat electrodes parallel in space, is less subject to undesired oscillations than a similar apparatus equipped with a "B" battery of the usual type. I have also found that a "B" 105

battery of flat cells used in circuits carrying currents of radio frequency makes the receiver somewhat more sensitive to weak signals. These effects may be due to a lower 5 internal resistance in the battery, but it is my belief that the improvement is mainly due to a more favorable magnitude and distribution of the capacity reactance of the battery. It will be apparent from the parallel 10 arrangement of the electrodes in the preferred arrangement, and from the manner of electrically connecting the cells of the battery, that the magnitude and distribution of the capacity reactance will be materially 15 different than with the usual arrangement of cells, but I am not aware of any reasoning by which it might be determined, a priori, that this difference would favorably affect the sensitiveness of a receiver. This 20 effect was discovered experimentally.

Whatever the true cause may be, I have found that improved results are obtained by arranging the electromotive units constituting the battery in a single row; and 25 especially good results are obtained when such units are constituted of electrodes presenting substantially plane surfaces. A flat cell battery of the type disclosed in the application of Carl S. Rider and Alton K. 30 Huntley covering improvements in batteries of dry cells and processes of assembling the same, filed March 11, 1922, Ser. No. 543,095, wherein the anodes and cathodes of adjacent cells are in direct contact, a single structural 35 element or "duplex electrode" preferably performing the functions of both the cathode of one cell and the anode of one of the adjacent cells, has given particularly favorable results.

In the drawing a 15-cell battery 2, of the 40 type described, is shown in vertical longitudinal section. The battery is build up of cells comprising flat mix cakes 3 spaced from electrodes 4 by sheets of pulpboard 5. The compositions of the mix and electrolyte, and the moisture content, may be determined in accordance with standard dry cell practice. Electrodes 4 consist of zinc plates 6 coated 45 on one surface with a non-corrodible conductive composition 7 containing graphite. One end electrode consists of a zinc plate 8; the other end electrode is a zinc plate spaced from adjacent elements by its coating 7. The end electrodes are connected to 50 binding posts 9 and 10.

For the purpose of definition, the individual cells of the battery may be considered as comprising an anode of zinc 6, and as a cathode the mix cake 3 mechanically separated 55 from each other by a pulp board sheet 5, made conductive by saturating it

with a solution of salts. The conductive coatings 7 serve to mechanically separate and electrically connect the individual cells.

The cells are assembled in a box 11 and 65 may be placed under compression by wedges 12. A plastic insulating material 13, such as pitch, is poured about the cells and serves effectively to insulate them. The battery 2 is suitably connected in circuit with an electron tube 14 and telephone 15.

With a battery of this type, not only is the space-economy for a given current output better than with types having plural rows of cylindrical cells, but the distance 75 between any pair of electrodes, like or unlike, is roughly proportional to the difference between their potentials. It will be apparent that this arrangement strongly favors the elimination of current leakage, 80 and it probably tends to produce a more constant capacitance. On actual test, the combination is found to be more free from uncontrollable disturbing influences than is a combination which includes plural rows of 85 cells.

An electron tube has been described as the device for controlling the action of the battery on the telephone, but other devices of similar action and requiring a battery or batteries of high-voltage type are equivalent to an electron tube in this connection. It is obvious that the controlling device need not be connected directly to the battery and telephone. 95

In view of these described and other obvious modifications, my invention is limited only by the appended claims.

I claim:

1. In combination, an electron tube and a 100 "B" battery connected to its plate, said "B" battery comprising a plurality of cells each having a substantially flat zinc anode, the zinc anodes being disposed close together and parallel in space and being substantially 105 completely overlapped.

2. The invention according to claim 1 in which one side of each anode is substantially entirely coated with a non-corrodible conductive composition, and the major portion 110 of one side of the cathode of an adjacent cell is in contact with the coating.

3. In combination, an electron tube and a "B" battery connected to its plate, said "B" battery comprising a plurality of cells 115 in electrical series, each cell provided with a zinc anode, the anodes of adjacent cells being overlapped and in substantially parallel spaced relation.

In testimony whereof, I affix my signature. 120

RAYMOND C. BENNER.
